UNITED STATES PATENT OFFICE.

DAVID WENTWORTH ROBB, OF AMHERST, NOVA SCOTIA, CANADA.

BOILER.

Application filed July 26, 1927. Serial No. 208,505.

This invention relates to improvements in boilers or furnaces and the like.

One object of the invention is to provide a boiler wherein the heat units of the products of combustion may be utilized with a higher degree of efficiency when the fire has been properly stimulated while, at the same time, when combustion is comparatively low, the path of the circulating products of combustion may be readily varied so as to stimulate combustion at the expense or loss of comparatively few heat units.

A further object of the invention is to provide, in a boiler of this type, a novel form of draft regulating mechanism.

With these and other objects in view the invention consists in certain novel details of construction, and combinations and arrangements of parts, all as will hereinafter be more fully described and the novel features thereof particularly pointed out in the appended claims.

In the accompanying drawings,—

Figure 1 is a longitudinal section through a boiler embodying the present improvements.

Fig. 2 is a sectional view on the line 2—2 of Fig. 1; and

Fig. 3 is a sectional view taken horizontally through the upper portion of the boiler.

While the invention, in various aspects, is not limited to any particular construction of boiler, the boiler shown in the present instance comprises outer and inner shells 10, 11, forming water spaces 12, a fire door 13 being provided at the front. If desired, door 13 may be provided with a carburetor 14 of the type shown in applicant's Patents No. 1,513,425 dated October 28, 1924, and No. 1,565,674, dated December 15, 1925. At its lower portion the front of the boiler is provided with a door 15 through which access may be had to ash pit 16 below the grate sections 17. The front grate section indicated at 17^a is capable of being dumped by an operating lever 18 at one side of the boiler while the remaining grate section 17 may be rocked for shaking down the fire by an operating lever 19 at the front of the boiler.

At the top of the combustion chamber there is a water space 20 formed by the top sections 10^a, 11^a, of the outer and inner shells and depending from the inner shell 11^a is a plurality of water tubes 21 which communicate with said water space 20. Preferably, these water tubes 21 are inclined somewhat, approximately ten degrees to the vertical, whereby a posi-

tive circulation of the water in said tubes is induced. By having the tubes inclined somewhat to the vertical the heated water circulates upwardly in a truly vertical direction 60 laying close to the upper sides of the inclined tubes while the colder water will circulate downwardly along the lower sides of said tubes. Water is supplied to the boiler through the inlet pipes 22 which communicate with the water spaces 12 at the base of the boiler while the heated water is discharged through the outlet 23 in the top section 10^a of the outer shell.

In order to give the depending tubes 21, as 70 well as the other heating surfaces in the upper portion of the boiler, the full benefit of the heat units carried by the products of combustion the smoke pipe 24 communicates with the combustion chamber 25 at the rear thereof 75 at which point there is a water baffle 26 extending from the inner shell section 11^a down to approximately the lower extremities of the depending tubes 21, said baffle having an internal passage 27 through which products 80 of combustion may flow from the combustion chamber 25 to the smoke pipe 24. At its sides said baffle 26 is formed with a water space 28 which communicates with the water space 20 in the upper portion of the boiler. If all 85 sides of the baffle 26 were made solid it will be apparent that the products of combustion in the combustion chamber, and especially those in the forward portion thereof, would rise in said chamber and circulate in a rather 90 tortuous path amongst the water tubes until they came into contact with said baffle whereupon they would be deflected downwardly before entering the internal passage 27 of said baffle from whence they escape to the smoke 95 pipe 24. Such a tortuous circulation of the products of combustion is highly desirable in order to utilize the greatest number of heat units therein but when the fire in the boiler is comparatively low, combustion cannot be 100 very quickly stimulated so long as the products of combustion are compelled to take this tortuous path in reaching the smoke pipe. Consequently, in the present invention, means are provided for permitting the products of combustion to escape from the upper portion 105 of the combustion chamber 25 directly to smoke pipe 24. This is preferably accomplished by having the front wall of the baffle 26 provided with a duct 29 through which 110 the products of combustion may reach the smoke pipe without passing through the in-

ternal passage 27 of said baffle. Ordinarily, one duct 29 is sufficient but it will be understood, of course, that the present invention is not to be limited to the use of a single duct.

5 When the fire in the boiler is low and it is desired to increase combustion the products of combustion are allowed to flow through the smoke pipe 24 to duct 29 but after the fire has been stimulated to the desired extent duct 10 29 is adapted to be closed by a valve 30 whereupon the products of combustion must then pass downwardly along the exterior wall of the baffle and flow upwardly through the internal passages 27 of said baffle. In this way, 15 comparatively all of the heat units are utilized as before mentioned.

To regulate the draft through the boiler the smoke pipe is provided with a rocking shut-off damper 31 adapted to be rocked on its center by an operating lever 33 connected to the shaft of said damper by a link 32. The smoke pipe 24 is also provided with a check damper 34 whose inner face has a projection 35 formed thereon and extending from the 20 shaft of said shut-off damper 31 is an arm 36 adapted to engage projection 35 on the check damper 34 when the shut-off damper 31 is moved to its closed position. As indicated in dotted lines in Fig. 1 this cooperation between 25 arm 36 and projection 35 is such that when the shut-off damper is completely closed the check damper will be fully opened. In accordance with the present invention, it is also preferred that valve 30 of duct 29 of baffle 30 be also actuated by the operating member 33. For this reason the shaft of the shut-off damper 31 is provided with a second arm 37 connected by a link 38 to said valve 30. As 40 shown in the drawings, link 38 has a pin and slot connection with arm 37 so that valve 30 may be adjusted toward and from said arm to coordinate the movements of valve 30 and the shut-off damper as desired. Preferably, this connection is such that when the shut-off 45 damper is in the vertical or fully opened position, the valve 30 is also fully opened, thereby giving a direct draft from the fire through the duct 29 in the water baffle. To move these parts to the positions named operating member 33 is moved inwardly toward the smoke pipe such movement of the parts permitting the damper 34 to fall by gravity to its closed position thereby giving a direct draft from the fire through the duct 29 to the smoke 50 pipe. A reverse movement of the operating member 33, however, will effect the opening of check damper 34 as before mentioned and will also move both the shut-off damper 31 and the valve 30 of duct 29 toward their 55 closed positions. The arrangement of the connections between the shut-off damper and valve is preferably such that when the shut-off damper is actually closed, the valve 30 will be fully closed forcing the hot gases to pass 60 around the bottom edge of the water baffle to

thereby give the depending tubes 21 and other heating surfaces in the upper portion of the boiler full benefit of the heat units carried by those gases. When the shut-off damper 31 is nearly closed for reduced heating, or night 70 regulation, the check damper 34 is preferably adapted to be partly opened checking the draft to a greater extent by a line of cold air to be drawn into the smoke pipe while the shut-off damper 31 is still partly open so that 75 there is an outlet for the smoke or waste gases. The regulation of the movement of the check damper 34, shut-off damper 31, and valve 30, may, however, be varied with respect to each other by adjusting the connection between the arm 37 and link 38 or by varying the positions of arms 36, 37, around the center of rotation of the shut-off damper 31. To retain operating member 33 in any desired position it may be provided with a 80 series of notches 39 adapted to cooperate with a suitable locking member or plate 40 at the front of the boiler.

What I claim is:

1. In a boiler or the like, the combination 90 of a smoke pipe for the combustion chamber, a baffle in said chamber having an internal passage throughout its length communicating with said smoke pipe, whereby products of combustion may traverse the full length 95 of said baffle, a damper controlling the flow of air through said passage, an auxiliary passage from said combustion chamber to said pipe, and means controlling the flow of air through said auxiliary passage.

2. In a boiler or the like, the combination 100 of a smoke pipe for the combustion chamber, an elongated baffle having a longitudinally extending passage therein through which products of combustion may flow from the 105 combustion chamber to said pipe, a cut-off duct in one wall of said baffle through which products of combustion may flow directly from the combustion chamber to the smoke 110 pipe, and means for regulating the flow of said products of combustion through the passage and the duct of said baffle.

3. In a boiler or the like, the combination 115 of a smoke pipe for the combustion chamber, an elongated baffle having a longitudinally extending passage therein through which products of combustion may flow from the combustion chamber to said pipe, a cut-off duct in one wall of said baffle through which products of combustion may flow directly 120 from the combustion chamber to the smoke pipe, means for closing said duct, and a shut-off damper for preventing the flow of products of combustion through said smoke pipe.

4. In a boiler or the like, the combination 125 of a smoke pipe for the combustion chamber, an elongated baffle having a longitudinally extending passage therein through which products of combustion may flow from the combustion chamber to said pipe, a cut-off duct in 130

one wall of said baffle through which products of combustion may flow directly from the combustion chamber to the smoke pipe, a shut-off damper for preventing flow of products of combustion through the smoke pipe, a valve for said duct, and connections between said valve and damper for closing said valve as said damper is closed, and for opening said valve when the damper is fully opened.

5 5. In a boiler or the like, the combination of a smoke pipe for the combustion chamber, an elongated baffle having a longitudinally extending passage therein through which products of combustion may flow from the combustion chamber to said pipe, a cut-off duct in one wall of said baffle through which products of combustion may flow directly from the combustion chamber to the smoke pipe, a shut-off damper for preventing flow of products of combustion through the smoke pipe, a valve for closing said duct, an operating member for opening and closing said damper, said valve being movable to opened or closed positions simultaneously with said

10 damper.

15 6. In a boiler or the like, the combination of a smoke pipe for the combustion chamber, an elongated baffle having a longitudinally extending passage therein through which products of combustion may flow from the combustion chamber to said pipe, a cut-off duct in one wall of said baffle through which products of combustion may flow directly from the combustion chamber to the smoke pipe, a shut-off damper for preventing flow of products of combustion through the smoke

20 pipe, a valve for closing said duct, an operating member for opening and closing said damper, said valve being movable to opened or closed positions simultaneously with said

25 damper.

6. In a boiler or the like, the combination of a smoke pipe for the combustion chamber, an elongated baffle having a longitudinally extending passage therein through which products of combustion may flow from the combustion chamber to said pipe, a cut-off duct in one wall of said baffle through which products of combustion may flow directly from the combustion chamber to the smoke pipe, a shut-off damper for preventing flow of products of combustion through the smoke pipe, a check-damper in said pipe, a valve for said duct in the baffle wall, and means for simultaneously opening or closing said valve

and shut-off damper, said check damper being simultaneously movable to open position when said shut-off damper is closed and to closed position when said shut-off damper is open.

7. In a boiler or the like, the combination of a smoke pipe for the combustion chamber, an elongated baffle having a longitudinally extending passage therein through which products of combustion may flow from the combustion chamber to said pipe, a cut-off duct in one wall of said baffle through which products of combustion may flow directly from the combustion chamber to the smoke pipe, a shut-off damper for preventing flow of products of combustion through the smoke pipe, a check-damper in said pipe, a valve for said duct in the baffle wall, and an operating member for simultaneously opening said check-damper and closing said shut-off damper and valve and for simultaneously opening said shut-off damper and valve, said check-damper being movable by gravity to its closed position when said shut-off damper and valve are opened by said operating member.

8. In a boiler, the combination of a smoke pipe for the combustion chamber, a series of depending water tubes in said chamber, a depending water baffle in said chamber having an internal passage extending throughout its length and communicating with said smoke pipe, and means for permitting products of combustion to flow directly from said combustion chamber to said smoke stack independently of the internal passage through said water baffle.

DAVID WENTWORTH ROBB.
